UNITED STATES PATENT OFFICE.

JAMES WINANTS TALLMADGE, OF ALBANY, NEW YORK, ASSIGNOR TO FRANK W. BEARDSLEY, OF BAYONNE, NEW JERSEY.

APPARATUS FOR THE MANUFACTURE OF CARBURETED HYDROGEN.

SPECIFICATION forming part of Letters Patent No. 484,475, dated October 18, 1892.

Application filed September 12, 1891. Serial No. 405,523. (No model.)

To all whom it may concern:

Be it known that I, JAMES WINANTS TALLMADGE, a citizen of the United States, residing at Albany, in the county of Albany and State 5 of New York, have invented certain new and useful Improvements in Apparatus for the Manufacture of Carbureted Hydrogen Gas, of which the following is a specification.

This invention relates to an apparatus for 10 the production of a carbureted hydrocarbon gas in which the hydrocarbon liquid is floated on the acid solution, said apparatus being especially adapted for the illumination of buildings from isolated plants.

15 The objects of this invention are to provide a safe portable gas apparatus of this character of comparatively-large capacity, which can be placed in the cellar or other convenient location within the building to be illuminated; to provide safe, easy, and convenient means for recharging the apparatus with the metal to be consumed in the production of the hydrogen gas without permitting the escape of the gas; to provide a safety-valve that 25 will not choke from condensation and which will prevent the hydrocarbon liquid from being forced out of the generating-compartment in case of undue gas-pressure, and to provide an automatic drip to free the service-pipe 30 from condensation without the escape of gas therefrom.

Figure 1 of the accompanying drawings represents a perspective view of the apparatus, parts of the tank being broken away, exposing the interior thereof, the metal tray and its supporting mechanism being shown in normal position. Fig. 2 represents a perspective view of the apparatus, the tray being swung out from the tank for replenishment. Fig. 3 represents a transverse section of the apparatus. Fig. 4 represents a vertical section, on an enlarged scale, of the safety-valve and hood. Fig. 5 represents a vertical section, on an enlarged scale, of the filling-drip device connected with the gas-governor.

Similar numerals of reference indicate corresponding parts in the different figures.

The tank 10, constituting a part of this gas 50 apparatus, may be disposed in the cellar or basement of a building to be illuminated or at any other convenient point within or adja-

cent thereto. This tank is elongated horizontally to enable it to hold a large quantity of acid solution and is preferably of such width 55 and height as to enable it to be passed through an ordinary window or door. It is preferably made up of wooden strips nailed together and provided with a lead or other suitable acid-proof and gas-tight lining 11. 60 The upper part of this tank is divided into a generating-compartment 12 and a reservoir-compartment 13 by a transverse partition 14, which extends downward from the top of the tank and terminates above the bottom thereof. A fixed deck 15 covers the generating-compartment, and a fixed deck 16 partially covers the reservoir-compartment.

A perforated tray 20, or its equivalent, for containing scrap-iron or other suitable material to be consumed in producing hydrogen gas is supported in the generating compartment, being pivoted at the ends of two dependent bent arms 21, attached to a plate 22, hinged to the deck 15 and constituting a partial cover for the reservoir-compartment. A segmental gear 23 is bolted to the hinged plate 22, and a bracket 24 is fastened to the front wall of the tank. A worm-shaft 25 is journaled in said bracket and carries a worm 26, which meshes with said segmental gear. This shaft is provided with a crank 27 at its outer end. When in its normal closed position, the plate 22 is fastened down by stud-bolts 28, disposed in the sides of the reservoir-compartment and projecting loosely through holes in said plate, and by nuts 29 on said bolts. By these means the tray can be withdrawn for replenishing, and restored to its normal position through the opening 30 beneath the transverse partition 14 and through the reservoir-compartment without the escape of hydrocarbon or gas. During its withdrawal and reinsertion the tray maintains a horizontal position and the worm prevents any sudden movement of the arms, which might disturb the liquids within the tank.

The top of the reservoir-compartment 13, between the closed deck 16 and the plate 22, 100 is closed by a movable cover 17.

The reservoir-compartment is provided with an automatic overflow and drawing-off device for carrying off an excess of the solution and

for use in emptying the tank when the solution needs to be renewed. This device comprises a siphon, whereof the short leg 30 is disposed in the reservoir, its lower end being 5 open near the bottom thereof and its upper end passing out through the end of the tank near the top thereof. The long leg 31 of the siphon extends downward below the bottom of the tank, preferably connecting with the 10 sewer when a sewer is accessible, being provided in such case with a trap 32 to prevent the rising of sewer-gas. The siphon is provided with a tube 33, which constitutes an upward extension of the long leg thereof. This 15 extension-tube is provided with a cock 34, which is located above the plane of the top of the solution, and consequently the acid of the solution cannot act injuriously therein. The upper end of this tube is provided with 20 a funnel 35 to receive water for starting the siphon.

A gas-eduction pipe 40, provided with a stop-cock 41, leads from the top of the generating-compartment to a gas-pressure governor 42, the outlet of said governer being connected with the service-pipe 43.

A compound device for supplying hydrocarbon and for freeing the service-pipe 43 from condensation is disposed in the top of 30 the generating-compartment 12, and comprises a pipe 50, extending above and below the deck and trapped by a U-shaped bend near the bottom of the generating-compartment, a branch-pipe 51, connecting said pipe 35 50 above the deck with the outlet of the governor, and a branch-pipe 52 for supplying hydrocarbon liquid, preferably extending to the outside of the building and closed when not in use by the cock 53 above the branch 51. 40 The branch 51 serves to automatically remove condensation from the service-pipe 43 and avoids the necessity of opening a petcock from time to time for the purpose, as usual in gas-governors.

45 A safety-valve is disposed in connection with the generating-compartment 12 to prevent the hydrocarbon liquid from being forced out of the generating-compartment in case of undue pressure. This safety-valve comprises 50 a dependent tube 60, extending downward through the deck 15 of the gas-generating compartment 12, and a float 61, having a hollow stem 62, adapted to slide vertically on said dependent tube. The stem 62 is of larger 55 diameter than the dependent tube 60, in order to permit the gas to pass through said stem around said tube. The lower end of the hollow stem 62 is closed and a small quantity of mercury is disposed therein, which forms a liquid seal for closing said tube. The float 61 is 60 of such gravity as to sink in the hydrocarbon and to float in the solution. The dependent tube is provided above the deck of the generating compartment with an offset 63 to prevent 65 the mercury from being blown out with the gas. An escape-pipe 64, preferably extending to the outside of the building, is connected to

the offset 63 by a hood 65, said hood being open at its bottom to permit the condensation that forms in the hollow stem 62 to drop 70 away when blown out before attaining a height sufficient to choke the pipe 64 and prevent the safety-valve from performing its proper function.

In the use of this apparatus the tank is 75 placed in the desired position and the proper pipe connections, as hereinbefore referred to, are made. The stop-cock 41 on the gas-eduction pipe 40 is closed and the stop-cock 34 on the pipe 33 is opened. The tank is then filled 80 in any suitable manner to the level of the horizontal part of the overflow-pipe 30 in the reservoir-compartment 13 with a dilute sulphuric-acid solution. This solution will rise in the generating-compartment high enough to choke 85 the trap 54 of the hydrocarbon-filling device 50, but not to a height sufficient to touch the tray 20 when said tray is normally disposed therein. A quantity of hydrocarbon liquid is then fed through branch 51 into the generating-compartment 12 and floats upon the surface 90 of the solution within said compartment, after which a small quantity of water is fed into the pipe 51 to push out the hydrocarbon remaining therein. Thus odor of hydrocarbon 95 about the apparatus is avoided. The crank 27 is then turned, whereby the tray 20 is swung downward from the generating-compartment 12, thence outward under the partition, and upward through the reservoir-compartment 100 13, being suspended in convenient position for filling. It is filled with scrap-iron and then swung into the tank and into normal position in the generating-compartment 12. The plate 22 engages the stud-bolts 28, and the nuts 29 are placed on said bolts and the plate locked. In this position the iron scrap is not submerged in the solution until the stop-cock 41 on the gas-eduction pipe is 105 opened and the gas turned on. Then the 110 pressure is relieved and the solution rises in the gas-compartment 12 and attacks the iron and hydrogen gas is generated, which rises through the layer of hydrocarbon liquid floating on the solution within the generating- 115 compartment and becomes impregnated with hydrocarbon vapor. The carbureted hydrogen gas thus formed in the generating-compartment passes out through the eduction-pipe 40 for supplying the burners connected 120 with the gas apparatus. When the burners are shut off, gas accumulates in the generating-compartment and the pressure thereof forces down the solution in said compartment until the level thereof falls below the tray 20 125 and the iron therein. The formation of gas then ceases. If sufficient solution remains in the pores of the iron to continue the generation of gas after the burners are shut off to such an extent as would cause the level of 130 the solution to fall below the lower end of the transverse partition 14 and permit the hydrocarbon to escape into the reservoir-compartment 13, the safety-valve will permit the gas

to blow off before the hydrocarbon can escape. The float 61 of said valve in such case descends until the mercury within the hollow spindle 62 falls below the lower end of the dependent tube 60, whereby the gas is permitted to escape downward through said hollow spindle, upward through said tube 60, and out through the offset 63 and escape-pipe 64 to the outside atmosphere. As undue pressure is removed, the level of the solution within the generating-compartment rises, carrying the floating valve upward, causing the mercury seal to close the lower end of the tube 60. A proper level of the solution is thus maintained in the generating-compartment and escape of the hydrocarbon is impossible. The blow-off pipe 62 is liable to become filled with condensation of the gas, which will be blown out when the safety-valve operates. The hood permits this condensation to escape, and hence it does not interfere with the operation of the blow-off.

When this gas apparatus is in use, the cock 34 of the combination overflow and draw-off pipe must be left open, and the pipes 30 and 31 will remove only the surplus solution in case the tank is overfilled. When it is necessary to renew the solution, said cock is closed and the funnel 35 is filled with water, after which the cock is opened and permitted to remain open until the funnel 35 is nearly empty. Then by closing said cock the siphon is started, which will empty the tank. It is imperative that this and all cocks about the apparatus are placed above the level of the acid solution. Otherwise they will be destroyed by the acid.

I am aware that a similarly-constructed gas apparatus has before been used; but in its construction there was no means provided for an overflow or for drawing off the spent solution; also, it required great strength, skill, and care to manipulate the tray; also, the safety-valve would choke from condensation and allow the hydrocarbon to escape from the gas-generating compartment into the reservoir-compartment, thereby endangering life and property, and also the service-pipe would choke from condensation, and thereby put the lights out, all of which made it of little or no commercial value. This invention obviates all elements of danger and the above-mentioned fatal objections.

I claim as my invention—

1. In a gas apparatus, the combination of a tank for containing an acid solution, bent hinged arms depending into said tank, a tray

for containing metal, pivoted to said arms, a gear fixed to said arms, a worm journaled adjacent to and meshing with said gear, and means for rotating said worm to swing said tray into and out of its normal position within said tank.

2. In an apparatus for producing carbureted hydrogen gas, the combination of a reservoir-chamber for containing an acid solution, a generating-chamber open at its lower end into said reservoir-chamber and terminating above the bottom thereof, a tray for holding metal to be acted upon by said solution, supported within said generating-chamber above the lower open end thereof, and an automatic blow-off valve connected with said generating-chamber for regulating the height of the acid solution therein, the outlet-pipe of said blow-off valve being provided with a hood open at its bottom and surrounding the end of said outlet-pipe for guiding the condensation therefrom.

3. In a gas apparatus, the combination of a generating-compartment for containing an acid liquor, a tray for containing metal, supported within said generating-compartment, a dependent tube extending through the top of said compartment, a float-valve adapted to float on said solution and provided with a hollow stem surrounding said dependent tube and with a mercury seal, an offset near the upper end of said tube, and a hood open at its bottom and surrounding said offset and provided with an escape-pipe extending above the hood.

4. In a gas apparatus, the combination of a generating-chamber, an eduction-pipe provided with a governor, and a drip-pipe extending from said governor into said generating-chamber and provided with a trap at its lower end.

5. In a gas apparatus, the combination of a generating-compartment for containing an acid liquor, a tray for containing metal scrap, supported in said compartment, a filling-pipe for hydrocarbon liquid, extending into said compartment and provided with a trap at its lower end, an eduction-pipe for the gas, and a drip-pipe for condensed matter, connecting said eduction-pipe with said filling-pipe.

In testimony that I claim the invention above set forth I affix my signature in presence of two witnesses.

JAMES WINANTS TALLMADGE.
